CLAIM

The ornamental design for a shoe upper, as shown and described.

DESCRIPTION

FIG. 1 is a first perspective view of a shoe upper showing our new design;

FIG. 2 is a second perspective view thereof;

FIG. 3 is a front view thereof;

FIG. 4 is a left side view thereof;

FIG. 5 is a right side view thereof; and,

FIG. 6 is a top view thereof.

The broken lines immediately adjacent to the photographic area represent boundaries of the design and form no part thereof. The broken lines depicting the remainder of the shoe upper are for the purpose of illustrating portions of the shoe upper that form no part of the claimed design.
